UNITED STATES PATENT OFFICE.

OWEN RICHARD WILLIAMS, OF DARLINGTON, ENGLAND.

RAIL-BEARING PLATE.

Application filed August 7, 1924. Serial No. 730,668.

To all whom it may concern:

Be it known that I, OWEN RICHARD WILLIAMS, a subject of the King of England, residing at Darlington, in the county of 5 Durham, in the Kingdom of England, have invented new and useful Improvements in a Rail-Bearing Plate, of which the following is a specification.

The invention relates to a rail bearing 10 plate, its object being to provide a plate of the kind having reduced bearing portions in contact with the rail, of generally improved construction and manufacture.

According to the invention the plate is 15 produced by pressing from a rectangular metal blank and comprises a central portion and lateral side portions, said central portion being of less thickness but greater length than said side portions and having 20 two rail seating portions formed thereon, and two longitudinal upstanding guides extending across the plate at the junction of the side and central portions. A plate of this form offers great advantages in manu- 25 facture over the ordinary drop-forged, stamped or cast plates, since the thinner portions are produced by squeezing the blank laterally and also into the portions which are required to be thicker in the finished article, the distribution of metal in the above 30 construction requiring a minimum of work to produce a plate of maximum service-ability. Preferably a boss is formed centrally on each side edge of the plate for the purpose of allowing any excess metal to be extruded from the pressing dies and thus 35 prevent risk of damage thereto.

The invention is illustrated in the accompanying drawings, in which:—

Figure 1 shows a plan view of a finished 40 plate; Fig. 2 is an elevation thereof; Fig. 3 is a cross section on line B—B of Fig. 1.

The bearing surfaces 1, 1 of the plate, which provide seating portions for the rail, are made relatively small and are slightly 45 inclined to the horizontal plane in order to minimize the rocking tendency of the plate as the load traverses the rail supported thereby, thus preserving the packing of the

ballast and reducing the forces which generate "creep", as is well known in the art. 50

In order to leave these bearing surfaces upon the blank, considerable metal must be pressed away, and this is provided for by making the cross section of the central portion 2 of the base of greater length than the thicker end portions 3, 3, thereof, which end portions approximate to the original dimensions of the blank. The metal squeezed in a transverse direction from the central portion 2 is mainly utilized in forming two longitudinal upstanding guides 4, 4 extending wholly across the plate and serving to locate the rail securely and correctly upon the bearing plate. A boss or lug 5 disposed centrally at each side edge allows surplus 60 metal to be extruded through these safety gaps. Holes 6 receive the necessary coach-screws, spikes or the like by which the plate and rail are secured to the sleeper.

The cross section at any part is approxi- 70 mately constant.

I claim:

1. A rail bearing plate of the kind described produced by pressing from a rectangular blank and comprising a central 75 portion and lateral side portions, said central portion being of less thickness but greater length than said side portions and having two rail seating portions formed thereon, and two longitudinal upstanding 80 guides extending across the plate at the junction of the side and central portions, substantially as and for the purpose set forth.

2. A rail bearing plate of the kind described produced by pressing from a rectangular blank and comprising a central portion and lateral side portions, said central portion being of less thickness but greater length than said side portions and having two rail seating portions formed 85 thereon, and two longitudinal upstanding guides extending across the plate at the junction of the side and central portions, and a boss centrally disposed on each side edge of the plate, substantially as and for 90 the purpose set forth.

OWEN RICHARD WILLIAMS.
